WATER HEATING UNIT FOR OIL BURNERS

William H. Wood, Jr., Ansonia, Conn.

Application March 6, 1940, Serial No. 322,451

2 Claims. (Cl. 126—53)

This invention relates to water heating units for oil burners, and more particularly a water heating unit for use with the common type of upright cylindrical burner now generally used in cooking ranges in a fire box located in front of the oven, and has for an object to provide a construction and arrangement of water heating unit which does not interfere with the heating of the oven by the burner, which absorbs heat from the burner which to a large extent might be wasted, and which is not liable to become overheated with consequent overheating and boiling of the water.

It is also an object of the invention to provide a water heating unit for range oil burners which is simple in construction and effective in operation, does not interfere with heating of vessels located over the burner, and does not interfere with the lifting and easy removal of the burner from its location in the fire box for cleaning, renewal or repair.

With the foregoing and other objects in view I have devised the construction and arrangement illustrated in the accompanying drawing forming a part of this specification, it, however, being understood that I am not limited to the specific construction and arrangement illustrated, but various changes and modifications may be employed within the scope of the invention.

In this drawing:

Fig. 1 is a longitudinal section of the forward portion of a cooking range taken substantially on line 1—1 of Fig. 2 and showing the burners and my improved water heating unit in top plan view located within the fire box;

Fig. 2 is a vertical section substantially on line 2—2 of Fig. 1;

Fig. 3 is a side elevation of the preferred form of heating unit removed from the stove and flattened out to more clearly show the construction;

Fig. 4 is a similar view of a modified construction; and

Fig. 5 is a top plan view thereof with a portion broken away to more clearly show the construction.

There are several types of water heating units for association with oil burners used in cooking ranges and which have caused considerable trouble and have definite objections. Usually there are two oil burners used in the fire box in front of the oven. If the water heating unit is a coil or other type of unit extending all the way around a burner it shuts off so much heat of the burner from the oven that the oven doesn't operate properly, and usually under such circumstances when the oven is used even for moderate

baking temperatures it is necessary to light the second burner. As in this arrangement the water heating coil or unit extends between the two burners the heat from the second burner added to that of the first burner heats the water too hot so that it boils. Another arrangement is to put the water heating coil or unit over the top of one of the burners. This doesn't interfere objectionably with heating of the oven, but does greatly interfere with the cooking of anything over the burner, and this arrangement also has the objection of heating the water too hot. It further interferes with the lifting out or removal of the burner for cleaning, renewal or repair.

With my improved construction and arrangement I have effectively overcome these objections. In the drawing a cooking range is indicated somewhat diagrammatically at 10 having the usual oven 14 in front of which is the fire box 12 with flue 13 leading from the fire box over the top of the oven and flue 14 connecting therewith at the back of the oven and extending forwardly and rearwardly under the oven and then to the chimney for circulating products of combustion from the burner around the oven in the usual manner. In the fire box 12 is located a pair of upright oil burners 15 and 16, preferably of the type having one or more perforated cylindrical shells 17 within which the vaporized oil is burned in the usual manner, an oil supply pipe 18 being shown diagrammatically leading from any suitable oil supply 19.

My improved water heating unit is shown at 20. This may be of different constructions but preferably as shown in Figs. 1, 2 and 3 comprises a tube or pipe bent back and forth in zig-zag relation in a direction circumferentially of the burner and with the different sections located one above the other and also preferably spaced from each other. Also, as shown in Figs. 1 and 2 they are curved horizontally in the direction of the circumference of the burner so as to lie substantially parallel with the surface of the outer shell 17. The convolutions, however, are of such a length as to embrace only a portion of the circumference of the burner as indicated by the arc 21 of Fig. 1, leaving the opposite side of the burner fully exposed. In the arrangement shown this unit preferably embraces approximately one-half of the burner, and is arranged on the outer side thereof opposite to the side on which the oven is located. It will also be seen that this coil or heating unit does not project far enough around the inner side of the burner to extend materially into the space between the two burners 15 and 16. It is there-

fore not subjected to any great extent to the heat from the burner 16, but receives the greater proportion of its heat from the burner 15.

It will also be seen from Fig. 1 that as it is located on the opposite side of the burner from the oven it does not interfere with the direct heating of the oven from the burner, as indicated by the lines 22 tending to represent broadly heat rays, but it does intercept and absorb the heat rays passing outwardly from the burner on the opposite side. This is heat which would ordinarily be largely lost as there is nothing on that side of the burner to be heated, and therefore this heating unit, by absorbing only heat which might to a large extent be otherwise wasted, increases the efficiency of the stove without interfering with the heating of the oven. Therefore the single burner 15 supplies sufficient heat to the oven for ordinary baking operations, but if a very hot oven is desired the second burner 16 may be operated. However, in view of the improved construction and arrangement of the water heating unit, the use of the second burner does not heat the water heating unit to an extent to overheat it and cause the water to boil. Also, the coils of the unit are spaced from each other to permit the passage of plenty of air laterally into the burner to support the combustion, and therefore the unit does not interfere with proper combustion or burning of the oil vapors in the burner.

A modified construction of heating unit is shown in Figs. 4 and 5 at 23. This comprises a hollow member having spaced inner and outer sheet metal side walls 24 and 25, and are curved in a direction circumferentially of the burner the same as the first form shown in Figs. 1 to 3. It is also when used located in the same position as the unit 20, that is, on the opposite side of the burner from the oven, and arranged so as not to extend materially into the space between the two burners. It may have one or more baffles 26 to increase the path of circulation of water through the element, and each element 20 or 23 may have inlet and outlet connections 27 and 28 for connection to a storage tank 29 to lead the cooler water to the unit from the tank and carry the heated water back to the tank. The form 23 of the unit if made with continuous walls may interfere somewhat with the flow of air to the burner and thus interfere with combustion on the side of the burner next to the heating unit. This may be cured by providing transverse tubes 30 through the walls of the unit 23 for conducting air to the burner, but this makes this construction much more expensive than the tubular construction shown in Figs. 1, 2 and 3 and therefore

this tubular construction is preferred. In each case it is preferred that the heating unit extend for substantially the full height of the burner as shown, but it will of course be understood if the water is sufficiently heated by a unit of less height such a unit may be employed if desired.

It will thus be seen that with this improved construction and arrangement the burner supplies direct heat to the oven, and the water heater in no way shields the oven from the heat of the burner. The heater takes the heat that is radiated in the direction away from the oven which would to a large extent be lost, and also does not interfere with the heating of the oven by the second burner, nor is the unit overheated by this burner. As the water heater is located at one side of the burner it does not interfere with the lifting out of the burner for renewal, cleaning or repair, and it also does not interfere with heating and cooking operations on the usual grids 31 in the top of the stove over the burner. It gives plenty of hot water without getting too hot and saves heat as it is on the outer side of the burner where there is nothing to be heated.

Having thus set forth the nature of my invention, what I claim is:

1. In a cooking range having an oven and a fire box at the front thereof, a pair of spaced upright oil burners in the fire box having upright cylindrical shells, an upright water heater comprising a pipe extending back and forth in vertically spaced zig-zag arrangement located closely adjacent on the opposite side of one of the burners from the oven and curved to embrace only approximately one-half the circumference of the burner so that the space between the burner and the oven is clear, said heater being also located on the opposite side of the first burner from the second burner whereby the space between the burners is clear, and means for leading water to and from the water heater.

2. In a cooking range having an oven and a rectangular firebox extending across the front thereof, a pair of laterally spaced upright oil burners in the fire box having upright cylindrical shells, an upright water heater comprising a pipe extending back and forth in vertically spaced zigzag arrangement and curved to embrace a portion only of one of the burners, said heater being located between said burner and the adjacent outer corner of the fire box whereby the space between the two burners and the oven are free, and means for leading water to and from the heater.
